UNITED STATES PATENT OFFICE.

HARRY M. SEAGERS, OF GENEVA, NEW YORK, ASSIGNOR TO HULSE MANUFACTURING COMPANY, OF GENEVA, NEW YORK, A CORPORATION OF NEW YORK,

EMBOSSING PRESS.

Application filed January 5, 1924. Serial No. 684,585.

To all whom it may concern:

Be it known that I, HARRY M. SEAGERS, a citizen of the United States, and resident of Geneva, in the county of Ontario and State 5 of New York, have invented certain new and useful Improvements in Embossing Presses (Case No. 7), of which the following is a specification.

This invention relates very particularly 10 to improvements in presses for forming signs, advertising cards and the like by punching characters from paper and forcing them into a sheet of card board or other backing, preferably of a contrasting color.

15 One of the main objects of the invention is to provide a simple and efficient type-holding means for the press. Another object of the invention is to provide a very simple, efficient means for holding lines of 20 type, said means being independently adjustable and removable from a type-holding frame. Another object of the invention is to provide a simple means for holding the type in any desired position on the line-holding means.

25 There are other important objects and advantages of the invention which will appear hereinafter.

In the drawings, Fig. 1 is a front elevation 30 of an embossing press with the invention applied thereto;

Fig. 2 a side elevation thereof;

Fig. 3 a vertical central sectional view taken on the line 3—3 of Fig. 1;

Fig. 4 a detail bottom plan view of one 25 corner of the type-holding frame;

Fig. 5 a plan view of the type-holding frame and the carriage to which said frame is attached;

Fig. 6 a side elevation of the type holding frame and carriage;

Fig. 7 a plan view of a type carrying bar;

Fig. 8 a front view of the type carrying bar shown in Fig. 7;

Fig. 9 a plan view of a spring clip for securing the type carrying bar in the type holding frame;

Fig. 10 a side elevation of the spring clip shown in Fig. 9;

Fig. 11 an outer end view of the type bar securing clip;

Fig. 12 a plan view of a type spacing

clip for holding the type in its adjusted position on the type carrying bar;

Fig. 13 a side elevation of the clip shown in Fig. 12; and

Fig. 14 a transverse sectional view taken on the line 14—14 of Fig. 7 showing the type operating on a sheet of paper or a sheet of card board.

The press illustrated in the drawings is constructed substantially as shown in application, Serial No. 570,589, filed June 24, 1922 and need not be described herein in detail. The type carriage and type holder described herein is especially adapted for use in a press of the kind illustrated and described in the aforesaid application for patent, but of course it is not necessarily limited to use in that type of machine.

The press body comprises an integral heavy metal casing of general rectangular form, the bottom wall 1 of which is adapted to rest upon a pedestal or other support and to be rigidly secured thereto if desired. The top wall 2 of the press body is connected to the bottom wall 1 by integral, vertical side walls 3 and 4. The top wall 2 is provided with a flat under surface 5 lying in a horizontal plane and said wall forms a fixed head or platen of the press. The shiftable head or bed of the press comprises a thick oblong metal block 6 having flat upper and lower surfaces lying in parallel, horizontal planes. The bed 6 slides vertically between the end walls 3 and 4 and is suitably guided. The bed 6 is forced upwardly through the medium of a steel cam shaft 7 having two flat faces 8 and 9 at diametrically opposite points. The cam shaft is provided with two arcuate diametrically opposed working faces 10 and 11. The surface 10 is slightly eccentric to the axis of the shaft while the surface 11 is concentric with the axis of the shaft. On one projecting end of the cam shaft is rigidly secured an operating handle 12 by means of which the cam shaft may be rotated.

The cam shaft 7 is interposed between two rigid and relatively heavy flat thrust plates 13 and 14. These thrust plates are shiftable edgewise in opposite directions by reason of their frictional contact with the cam shaft when the hand lever is operated. A set of anti-friction rollers 15 is interposed

between the upper thrust plate 13 and the under face of the bed 6 of the press. A set of anti-friction rollers 16 are interposed between the lower face of the thrust plate 14 and a rigid portion of the press frame. It is manifest that by rotating the cam shaft the bed 6 will be moved upwardly for the pressing operation.

The card-holding carriage comprises a broad flat plate or base 17 which rests upon and is slidable over the flat top face of the bed 6. This plate is slidably and detachably held to the bed, and guided to move directly fore-and-aft thereof by means of a steel rod 18 having a sliding fit in a hole 19 bored horizontally through the bed 6 from front to rear midway the ends of the bed. The rod 18 may be inserted in, and withdrawn end-wise from, the hole 19 when the carriage is detached therefrom. The carriage is attached to the guide and retaining rod 18 by inserting the reduced forward end of the rod in a hole formed in a flange or tongue stamped downwardly from the forward end 25 of the plate 17 and then passing a screw through a hole in the rear of the plate 17 and into a threaded hole in the rod 18, said screw passing through a spacing sleeve interposed between the plate 17 and the rod 18. 30 By removing the screw the rod may be detached from the carriage and then the rod and carriage removed from the press. When the parts are assembled the carriage is held against movement in all directions relatively 35 to the body except a sliding movement fore-and-aft of the press. The upper surface of the plate is flat and smooth and is designed to receive the card board into which the sign characters are to be impressed. The forward 40 end of the carriage is provided with a suitable handle 20 by means of which it may be readily shifted back and forth to the desired position in the press.

A swinging type-holding frame 21 is pivotally mounted on the carriage 17 near the rear end thereof. This frame consists of the two side bars 22 connected at their forward ends by the forward cross bar 23 and at their rear end by the rear cross bar 24. The 50 type-holding frame is an open frame substantially equal in width to the carriage 17 and the side bars thereof are provided with transverse scale marks 25 by means of which the type-carrying cross bars are accurately 55 aligned in parallel relation across the carriage. The rear end of the type-holding frame is mounted on pivots 26 which are supported on the forward ends of flat springs 27 rigidly secured to the upper surface of the carriage. These springs are offset and stand above the upper surface of the carriage so that the type-holding frame is yieldably supported by said springs a short distance above the surface of the carriage and may yield 60 downwardly toward the carriage. The rear

cross bar 24 is rigidly connected to the side bars 22 by means of corner plates 28 which bridge the joints between the ends of the cross bar 24 and the inner side edges of the side bars 22. These corner plates extend 70 rearwardly and form a part of the hinge connection between the type-holding frame and the springs 27. The yielding connection between the type-holding frame and the carriage is to permit the holding-frame to be 75 forced downwardly toward the carriage, as will be hereinafter described, in the operation of the press. This yielding connection also permits the type to be faced squarely 80 against the paper and the card board. By reason of the permanent connection between the type-holding frame and the table 17 the two parts may be moved together back and forth through the press. By drawing the table forward to the position shown in Fig. 85 2 the type-holding frame may be thrown upwardly and rearwardly, leaving the upper surface of the table free so that the card board and paper that is to be operated upon may be quickly and accurately placed in position thereon. The type-holding frame will be free to slide back and forth with the carriage in the space between the platens 6 and 2 when the movable pressing platen 6 is lowered, as shown in Fig. 3.

The embossing type are adapted to be mounted on type-carrying bars 29. These bars are preferably thin strips of metal beveled along their longitudinal edges and rounded at their ends. The bars are beveled downwardly so that their upper surfaces are slightly narrower than their lower surfaces. These bars are detachably and adjustably connected to the side bars of the type-holding frame by spring clips 30. These 100 clips are substantially U-shape and are of the same width as the bars 29. The upper member 31 of each clip is formed along its longitudinal side edges with depending gripping flanges 32 which are adapted to fit 110 down over the longitudinal side edges of the bars 29. The inward or free end of the upper member 31 is bent upwardly to form the upwardly and inwardly inclined flange 33. The purpose of this flange is to enable 115 the clip to be readily slid inwardly over the end of the bar 29. The ends of these bars are beveled, as shown clearly in Fig. 7 so that the flange 33 will easily ride up over said beveled portion when inserting the clips 120 in clamping position. As shown clearly in Fig. 10 the clips are slid inwardly and embrace between their upper and lower members, the side bars of the type-holding frame and the ends of the type-carrying bar. These 125 clips are of sufficient strength to prevent any slight accidental shifting of the type-carrying bars in the type-holding frame, but as they form a yielding clamping connection 130 between the bars, the type-carrying bars may

readily be shifted in the type-holding frame to place them in the desired position. When it is desired to remove the type carrying bars it is only necessary to detach the clips 30 5 thus leaving the type-carrying bars to be removed from the type-holding frame. By reference to Fig. 11 it will be observed that the gripping flanges 32, when the clip is in position, will lie along the beveled longitudinal edges of the type-carrying bar and hold the clip in position.

The press is adapted for use with sets or fonts of embossing type of various sizes and styles, said type comprising blocks 34 having the usual cutting type faces 35. Each type is provided in its back or upper non-printing surface with an under cut or dove tail groove 36 adapted to receive a type carrying bar, as shown clearly in Fig. 14. The 10 transverse grooves of the type are accurately cut so that the type when threaded on the type-carrying bars will be accurately aligned so that the base lines of the type will be in accurate alignment across the 15 type-holding frame. By this means all the type on a type-carrying bar will be accurately aligned without regard to the size of the letter and without regard to the character of the letter. This is clearly illustrated in Figs. 7 and 8 of the drawings. In 20 order that the type may be accurately and properly positioned on the type-carrying bars spacing clips 37 are employed. These 25 clips are of spring metal and are formed with a body part 38 and upwardly and inwardly turned gripping fingers 39. Each gripping finger is formed at its inner end with an upwardly and inwardly inclined gripping flange 40 which is adapted to bear 30 on the beveled longitudinal edge of the type-carrying bar. These spacing clips are slid 35 on the bars from the ends thereof with the body portion 38 under the bar and the flanges 40 in engagement with the beveled 40 longitudinal edges of the bar. The upper edges of the flanges 40 are flush with the upper surface of the bar 29 when the spacing clips are in position, and no portion of the spacing clip projects above the upper 45 surface of the said bar 29. The under cut 50 grooves 36 in the types are equal in depth to the thickness of the type-carrying bars so that the body of said types will not project above the upper surface of the bars but will 55 be flush therewith. This is desirable when the type-holding frame and the type are between the platens for the pressing operation.

At the rear of the carriage, and extending transversely thereof, is a forwardly facing 60 card gauge and clip 41 under which the rear edge of the card board sheet is adapted to be placed. By means of this clip and gauge the card board sheet may be quickly and accurately placed on the carriage in proper 65 position to receive the type impression.

The upper platen 2 of the press is provided with channels 42 at its ends to receive the clips 30 on the ends of the type-carrying bars which are between the platens.

To facilitate the assembly of the type on the type-carrying bars the upper non-printing faces of the type are stamped with the character of the type so that the reading matter of the sign may be read from the back or top of the type-holding frame when 70 it is all assembled.

The operation is as follows:

The carriage is drawn forward to the position shown in Fig. 2. The type to form each line of the reading matter of the sign 80 are slid endwise on a type-carrying bar and placed in proper position thereon. Spacing clips are then slid on the bar from each end to lock the type in the desired position on the bar. It will be understood, 85 of course, that the spacing clips may be used between letters, between words and at the ends of words. When the type are properly arranged on a type carrying bar said bar is placed across the type-holding frame and 90 secured in position thereon by means of clips 30. When the bar has been clipped to the holding frame it may be adjusted along the side bars thereof to the desired position. The transverse gauge marks 25 on the side 95 bars of the holding-frame assist in properly placing the type-carrying bars. By arranging one longitudinal edge of the type-carrying bar on corresponding marks on the two side bars the type-carrying bar will be correctly placed transversely of the holding frame. All of the type-carrying bars may be accurately placed in parallel arrangement by this means and, of course, they may be suitably placed apart along said side bars. 100

After the type are arranged in the holding frame the said frame may be swung upwardly and rearwardly to the position shown in dotted lines in Fig. 2. The card board on which the sign is to be made is now placed 110 on the carriage with its rear edge under the gauge clip 41, and a sheet of colored paper, or pieces of variously colored paper, placed thereon in proper position to be engaged by the type. The type-holding frame is then 115 swung forwardly and downwardly until the type rest on the paper. The position of the type with respect to the paper and card board is noted and the proper arrangements and proper relative positions of the parts are assured. When proper registration is obtained the carriage is slid rearwardly to bring the type between the platens. The 120 operating handle is then pulled rearwardly and downwardly to elevate the platen 6 and to cause the type to engage the under surface of the head 2. This forces the type into the card board, cutting the desired letters and forcing the cut out letters into the 125 card board in the usual manner of presses 130

of this type. In making large signs a plurality of successive pressing operations are necessary, the carriage being moved rearwardly in successive steps and after each 5 pressing operation to bring a new set of type between the platen. When the pressing operation is completed the carriage is drawn forwardly again to the position shown in Fig. 2, the type holding frame swung upwardly and rearwardly and the card board 10 sign removed from the carriage.

It is manifest that the yielding connection between the type-holding frame and the carriage 17 permits the type-holding frame 15 to be maintained parallel with the face of the carriage during all operations. The spring support for the type-holding frame yields during the pressing operation.

What I claim is:

20 1. An embossing apparatus comprising a bed, a platen, means for imparting relative movement between the bed and platen, a type-holding frame slidable transversely of the bed and into and out of position between

25 the bed and platen and rockable away from said bed, means for yieldingly supporting the type-holding frame to permit said frame to yield bodily in the pressing operation, type-carrying bars, and means for removably attaching said bars to the type-holding frame.

30 2. An embossing apparatus comprising a bed, a platen, means for imparting relative movement between the bed and platen, a carriage slidable transversely of the bed and between the bed and the platen, a type-holding frame pivotally connected at its rear end to said carriage, means for yieldingly supporting the said type-holding frame at 35 its pivotal connection with the carriage, type-carrying bars, and means for detachably connecting said bars to the type-holding frame.

35 3. An embossing apparatus comprising a bed, a platen, means for imparting relative movement between the bed and platen, a carriage slidable transversely of the bed and between the bed and the platen, a type-holding frame pivotally connected at its rear

40 end to said carriage, means for yieldingly supporting the said type-holding frame at its pivotal connection with the carriage, type-carrying bars, means for detachably connecting said bars to the type-holding frame, and a card gauge mounted on the carriage near the rear end thereof.

45 4. An embossing apparatus comprising a bed, a platen, means for imparting relative movement between the bed and platen, a carriage slidable transversely of the bed and between the bed and the platen, a type holding frame connected to said carriage and yieldingly supported for a bodily movement toward the carriage, and means for removably mounted type in said holding frame.

5. An embossing press comprising a bed, a platen, means for imparting relative movement between the bed and the platen, a rod slidable transversely through the bed and fore-and-aft of the press, a carriage rigidly connected to said rod and slidable fore-and-aft of the press between the platen and bed, a type-holding frame pivotally connected at its rear end to the carriage and slidable with the carriage transversely of the bed into and out of position between the bed and platen and rockable away from the carriage when withdrawn from between the bed and the platen, and means for removably mounting type in said holding frame. 75

6. An embossing press comprising a bed, a platen, means for imparting relative movement between the bed and the platen, a rod slidable transversely through the bed and fore-and-aft of the press, a carriage rigidly connected to said rod and slidable fore-and-aft of the press between the platen and bed, a type-holding frame pivotally connected at its rear end to the carriage and slidable with the carriage transversely of the bed into and out of position between the bed and platen and rockable away from the carriage when withdrawn from between the bed and the platen, and means for removably mounting type in said holding frame. 80

7. An embossing press comprising a bed, a platen, means for imparting relative movement between the bed and the platen, a rod slidable transversely through the bed and fore-and-aft of the press, a carriage rigidly connected to said rod and slidable fore-and-aft of the press between the platen and bed, a type-holding frame pivotally connected at its rear end to the carriage and slidable with the carriage transversely of the bed into and out of position between the bed and platen and rockable away from the carriage when withdrawn from between the bed and the platen, type-carrying bars, and means for detachably connecting said bars to the type-holding frame. 95

8. An embossing press comprising a bed, a platen, means for imparting relative movement between the bed and the platen, a rod slidable transversely through the bed and fore-and-aft of the press, a carriage rigidly connected to said rod and slidable fore-and-aft of the press between the platen and bed, a type-holding frame pivotally connected at its rear end to the carriage and slidable with the carriage transversely of the bed into and out of position between the bed and platen and rockable away from the carriage when withdrawn from between the bed and the platen, type-carrying bars, means for detachably supporting type on said bars, and means for detachably and adjustably connecting said bars to the type-holding frame. 100

9. An embossing press comprising a bed, a platen, means for imparting relative movement between the bed and the platen, a rod slidable transversely through the bed and fore-and-aft of the press, a carriage rigidly connected to said rod and slidable fore-and-aft of the press between the platen and bed, a type-holding frame pivotally connected at its rear end to the carriage and slidable with the carriage transversely of the bed into and out of position between the bed and platen and rockable away from the carriage when withdrawn from between the bed and the platen, type-carrying bars, means for detachably supporting type on said bars, and means for detachably and adjustably connecting said bars to the type-holding frame. 105

10. An embossing press comprising a bed, a platen, means for imparting relative movement between the bed and the platen, a rod slidable transversely through the bed and fore-and-aft of the press, a carriage rigidly connected to said rod and slidable fore-and-aft of the press between the platen and bed, a type-holding frame pivotally connected at its rear end to the carriage and slidable with the carriage transversely of the bed into and out of position between the bed and platen and rockable away from the carriage when withdrawn from between the bed and the platen, type-carrying bars, means for detachably supporting type on said bars, and means for detachably and adjustably connecting said bars to the type-holding frame. 110

11. An embossing press comprising a bed, a platen, means for imparting relative movement between the bed and the platen, a rod slidable transversely through the bed and fore-and-aft of the press, a carriage rigidly connected to said rod and slidable fore-and-aft of the press between the platen and bed, a type-holding frame pivotally connected at its rear end to the carriage and slidable with the carriage transversely of the bed into and out of position between the bed and platen and rockable away from the carriage when withdrawn from between the bed and the platen, type-carrying bars, means for detachably supporting type on said bars, and means for detachably and adjustably connecting said bars to the type-holding frame. 115

12. An embossing press comprising a bed, a platen, means for imparting relative movement between the bed and the platen, a rod slidable transversely through the bed and fore-and-aft of the press, a carriage rigidly connected to said rod and slidable fore-and-aft of the press between the platen and bed, a type-holding frame pivotally connected at its rear end to the carriage and slidable with the carriage transversely of the bed into and out of position between the bed and platen and rockable away from the carriage when withdrawn from between the bed and the platen, means for yieldably supporting the type holding frame at its pivotal connection with the carriage to permit the said frame 120

13. An embossing press comprising a bed, a platen, means for imparting relative movement between the bed and the platen, a rod slidable transversely through the bed and fore-and-aft of the press, a carriage rigidly connected to said rod and slidable fore-and-aft of the press between the platen and bed, a type-holding frame pivotally connected at its rear end to the carriage and slidable with the carriage transversely of the bed into and out of position between the bed and platen and rockable away from the carriage when withdrawn from between the bed and the platen, means for yieldably supporting the type holding frame at its pivotal connection with the carriage to permit the said frame 125

14. An embossing press comprising a bed, a platen, means for imparting relative movement between the bed and the platen, a rod slidable transversely through the bed and fore-and-aft of the press, a carriage rigidly connected to said rod and slidable fore-and-aft of the press between the platen and bed, a type-holding frame pivotally connected at its rear end to the carriage and slidable with the carriage transversely of the bed into and out of position between the bed and platen and rockable away from the carriage when withdrawn from between the bed and the platen, means for yieldably supporting the type holding frame at its pivotal connection with the carriage to permit the said frame 130

to have a bodily movement toward the carriage during the pressing operation, and means for removably mounting type in said holding frame.

9. A type-holding frame for embossing presses, a support for said frame movable transversely of the press to adjust the said frame to proper operative position, type-carrying bars adapted to extend transversely

10 of the holding frame, means for adjustably supporting type on said bars, and removable spring clips for detachably and slidably connecting the ends of said type-carrying bars to the type-holding frame.

11. A type-holding frame for embossing presses, a support for said frame movable transversely of the press to adjust the said frame to proper operating position, type-carrying bars adapted to extend transversely

20 of the holding frame, means for adjustably supporting type on said bars, and removable substantially U-shape spring clips adapted to embrace the type-holding frame and the ends of the type-carrying bars and detach-

25 ably and slidably connecting the said bars to the said frame.

11. A type-holding frame for embossing presses, a support for said frame movable transversely of the press to adjust the said

30 frame to proper operative position therein, type-carrying bars adapted to extend transversely of the holding-frame, type adjustable along said bars, detachable means for holding said types in their adjusted positions on said bars, and removable spring clips detachably connecting the ends of said type carrying bars to the type-holding frame.

12. A type-holding frame for embossing 40 presses, a support for said frame movable transversely of the press to adjust the said frame to proper operative position therein, type-carrying bars adapted to extend transversely of the holding frame, said bars being

45 beveled along their longitudinal edges, type having under cut transverse recesses in their non-printing faces and adapted to be slid into engagement with the beveled type-carrying bar, spring spacing clips adapted

50 to be slid along the longitudinal edges of the type-carrying bars to adjustably lock the type in position thereon, and removable spring clips detachably connecting the ends of said type-carrying bars to the type-holding frame.

13. A type-holding frame for embossing 55 presses, a support for said frame movable transversely of the press to adjust the said frame to proper operative position therein, type carrying bars adapted to extend transversely of the holding frame, said bars being beveled along their longitudinal edges,

60 type having under cut transverse recesses in their non-printing faces and adapted to be slid into engagement with the beveled

type-carrying bar, said recesses being of sufficient depth to receive the type-carrying bar wholly within them whereby the upper surface of the bar and the upper non-printing surfaces of the type will be flush, spring 70 spacing clips adapted to be slid along the longitudinal edges of the type-carrying bars to adjustably lock the type in position thereon, and removable spring clips detachably connecting the ends of the said type-carrying bars to the type-holding frame. 75

14. A type-holding frame for embossing presses, a type carrying bar adapted to extend transversely of the holding frame, means for adjustably supporting type on 80 said bar, and removable spring clips for detachably and slidably connecting the ends of said type-carrying bar to the type-holding frame, each of said clips being substantially U-shape and adapted to straddle the 85 end of the type-carrying bar and the adjacent side of the type-carrying frame and formed with flanges to engage the opposite side edges of said bar.

15. A type-holding frame for embossing 90 presses, type-carrying bars adapted to extend across the holding frame, said bars being beveled along their longitudinal edges, type having undercut transverse recesses in their non-printing faces and adapted 95 to be slid into engagement with the beveled type-carrying bar, means detachably connecting the ends of said type-carrying bars to the type-holding frame, and spring spacing clips adapted to be slid along the longitudinal edges of the type carrying bars to adjustably lock the type in position thereon, each of said clips being formed of 100 a strip of sheet metal bent upon itself at its ends and looped at the bends and having 105 its free opposed ends formed to engage the opposite beveled edges of its type-carrying bar and its central portion adapted to extend across and bear upon said bar.

16. An embossing apparatus comprising 110 a bed, a platen, means for imparting relative movement between the bed and platen, a carriage slidable transversely of the bed and between the bed and the platen, a pair of flat springs secured to the upper side 115 of the carriage near its rear end and having free forwardly extending ends off-set above the upper surface of the carriage, a type-holding frame, means for pivotally connecting the rear end of said type-holding 120 frame to the free off-set ends of the said flat springs, whereby the type-holding frame may yield bodily toward the carriage, and means for removably mounting 125

130 type in said holding frame.

17. A type-holding frame for embossing presses, a support for said frame movable transversely of the press to adjust the said frame to proper operative position therein, a type-carrying bar adapted to extend 130

transversely of the holding frame, said bar justably lock the type in position thereon, being beveled along its longitudinal edges, and means detachably connecting the ends of said type-carrying bar to the type-holding frame.

- 5 be slid into engagement with the beveled type-carrying bar, devices adjustable longitudinally of the type-carrying bar to ad-

In testimony whereof I hereunto affix my signature.

HARRY M. SEAGERS.
